PROJECTILE

George Norman Albree, Winchester, Mass.

Application February 5, 1942, Serial No. 429,669

9 Claims. (Cl. 102—50)

This invention relates to projectiles and it has for its principal object to provide a novel projectile which, during flight, will have an increased sustained velocity, due partly to a reduction in the vortex drag to which a projectile is normally subjected during flight, and partly to an improved ballistic form by which the head pressure on the projectile is reduced.

The present improvements may be embodied in projectiles of any calibre and also in projectiles having a solid body as well as in projectiles of the explosive type.

In order to give an understanding of the invention, I have illustrated it as it might be embodied in a projectile having a solid body and which is mounted in a "case" containing the explosive charge or propellant, but, as stated above, the invention is equally applicable for projectiles of large calibre that are not mounted in a case.

In the drawing,

Fig. 1 is a sectional view through the projectile embodying my present invention and showing the projectile before it has been discharged from the firearm.

Fig. 2 is a sectional view showing the projectile as it is moving through the barrel of the firearm.

Fig. 3 is a sectional view showing the projectile in flight.

Fig. 4 is a fragmentary sectional view showing a slightly different embodiment of the invention.

Fig. 5 is a fragmentary sectional view showing a still different embodiment of the invention.

In the drawing, 1 indicates the body of a projectile which is made in accordance with the invention and which is shown as mounted in the end 2 of a case 3 carrying the usual explosive charge or propellant 4. The projectile body 1 is formed with an axial bore 5 in which is received a tubular core member 6 which is somewhat longer than the projectile body 1 and is capable of limited movement in an axial direction. The forward end 7 of this core member 6 is exteriorly tapered, and when the member is in its operative position, shown in Figs. 2 and 3, which is the position it occupies during flight, said tapered tip projects beyond the end 8 of the projectile body 1 and forms the tip of the projectile nose.

In the preferred embodiment of the invention, the tip portion 7 of the core 6 is not only tapered, but it is tapered on a slightly concave curvature 9 and this curvature is such that when the core 6 is in its forward position, the concave curvature 9 merges into the convex curvature 10 of the

forward end of the projectile body 1, thereby producing an ogee curvature to the projectile nose which improves the ballistic form of the projectile. The tip end 7 of the core member 6 terminates in a sharp annular edge 11.

A projectile having the construction shown in Fig. 3 will have an increased sustained velocity because during the flight of the projectile, a stream of air under pressure will flow through the passage 17 in the core member 6, as indicated by the arrows *a* in Fig. 3, and this air will be delivered from the passage directly in the rear of the traveling projectile and will thus very materially reduce the vacuum conditions which tend to develop in the area 20 immediately in the rear of the projectile and thereby correspondingly reduce the vortex drag on the projectile. Furthermore, as stated above, the exterior shape of the tip 7 of the core gives to the projectile an improved ballistic form which results in a decreased head resistance. The sharp edge 11 of the core 6 cuts or bores its way through the air with a minimum of resistance and the ogee curve 9, 10 provides a shape which promotes free flow of air around the projectile with a minimum resistance, thereby correspondingly reducing the head pressure on the projectile.

The axial bore 5 in the projectile body is provided at its rear end with a portion 12 of enlarged diameter which provides an interior annular shoulder 13 between the two portions of the bore of different diameter. The tubular core member 6 is provided at its rear end with a portion 14 of enlarged diameter which provides an annular exterior shoulder 15 between the two portions of different diameter. The main body of the tubular core member 6 will preferably have a sliding fit with the portion of the bore 5 of smaller diameter while the enlarged base end 14 of said core will have a press fit with the portion 12 of the bore of larger diameter.

In order to provide appropriate protection for the tapered end 7 of the core member while the projectile is being handled or manipulated preparatory to its being fired, the core member 6 is constructed so that it can be moved backwardly in the projectile body 1 into a retracted position in which the tapered end 7 thereof is located within the bore 5 as shown in Fig. 1.

The enlarged base end 14 of the core and the enlarged portion 12 of the axial bore are of such length that when the core is in its retracted position, the forward end of the enlarged portion 14 of the core will be entered slightly into the

outer end of the enlarged portion 12 of the bore as shown in Fig. 1.

Associated with the inner end of the core 6 is a sealing member 16 for closing the rear end of the opening 17 through the core until after the projectile has been fired. After the projectile has left the barrel of the firearm, however, said sealing member becomes dislodged, thus opening the passageway 17 for the flow of air therethrough, as above described.

The sealing member 16 may be temporarily secured to the core member 6 in any suitable way, as by means of a ring of cement or other adhesive 18.

When the gun is fired, the pressure developed by the combustion of the propellant 4 will move the core member 6 forwardly from its retracted position shown in Fig. 1 to its forward operative position shown in Fig. 2, in which position the tapered tip 7 of the core member projects beyond the front end 8 of the projectile body and forms the tip of the nose of the projectile. As the core member moves forward, the air which is trapped in the portion 12 of the bore between the shoulders 15 and 13 will act as a shock absorber and will have a cushioning effect on the forward movement of the core thereby controlling its movement and reducing the force of the impact of the shoulder 15 against the shoulder 13. Since the portion of the core of smaller diameter has a running fit in the bore, such air will eventually be forced forwardly to the nose of the projectile between the exterior surface of the core and the interior wall of the bore.

It is quite desirable to provide some means for controlling the forward movement of the core for the purpose of reducing the force of the impact between the shoulders 15 and 13 when the core member is brought to rest at the end of its forward movement, and while one way of accomplishing this is by means of the cushioning effect of the air between said shoulders, yet other means of accomplishing this end might be employed without departing from the invention, such, for instance, as providing the exterior surface of the core with a coarse screw thread 50 which engages a similar interior screw thread formed in the wall of the bore as shown in Fig. 5, (wherein the core is indicated at 6b and the projectile body at 1b), whereby the force exerted against the rear of the core when the propellant 4 is detonated will cause said core to turn in the bore as it moves forward. Such screw threads may be arranged to give the core a turning movement either in the direction in which the projectile is rotated on its axis by the rifling of the barrel of the gun or in a direction opposite to such rotation of the projectile body.

The sealing member 16 is shown as being slightly larger in diameter than the portion 14 of the core member, and the parts are so designed that when the core member has reached its forward position shown in Fig. 2 with the shoulder 15 thereof seated against the shoulder 13 of the projectile body, the peripheral portion of the sealing member 16 will be seated against the face 19 of the base of the projectile body 1 as shown in Fig. 2. Because the sealing member 16 has a larger diameter than the base portion 14 of the core member, said member will not only close the passage 17 but will also prevent any leakage of gas through the joint between the portion 14 of the core and the interior wall of the portion 12 of the bore.

The face of the base of the projectile is prefer-

ably cone-shaped as shown at 19 although this face might have any other desirable shape without in any way departing from the invention.

The movement of the core member forwardly from the position shown in Fig. 1 to that shown in Fig. 2 will disintegrate the cement or adhesive 18 if the latter has not already been disintegrated or consumed by the heat generated by the detonation of the propellant 4.

10 While the projectile is traveling through the bore of the firearm, the sealing member 16 will be retained onto its seat by the pressure within the firearm thereby maintaining the passage 17 closed.

15 After the projectile has been discharged from the muzzle of the gun, then the sealing member 16 will be dislodged from its operative position partly by the vacuum conditions which tend to develop immediately in the rear of the projectile and partly by the pressure of the air in the passage 17.

20 After the sealing member 16 has thus been dislodged as shown in Fig. 3, then the passage 17 is open for the free flow of air therethrough as above described.

25 The provision of the central passage 17 through the projectile and the shape of the nose of the projectile combine to produce a projectile which will have an increased sustained velocity due partly to the reduction of the vortex drag and partly to the reduction in head resistance.

At the rear end of the core member 6, the wall of the passage 7 curves outwardly as shown at 21 to form a divergent end 22 for said passage.

30 This curvature 21 is important as it provides for the easy flow of air outwardly toward the periphery of the projectile base without establishing eddy currents. The stream of air which flows through the passage 17 will thus be delivered to

35 the peripheral portion of the vortex as well as to the central portion, thereby more effectively killing or reducing the vacuum conditions which tend to develop at this point. In Fig. 4 there is shown a modification of the invention in which the tip portion of the core has a convex instead of a concave curvature. In this embodiment, the projectile body is indicated at 1a and the movable hollow core is shown at 6a, the latter having the passage 17a therethrough. The tip 40 end of the core 6a has a convex curvature 9a which is a continuation of the convex curvature of the body at the base of the nose so that the portion of the core which projects beyond the end 8a of the body when said core is in operative position has a convex instead of concave curvature. In this construction, however, the extremity of the core presents the sharp edge 11a as in the other embodiment of the invention.

45 Although the invention has been herein shown as embodied in a projectile having a solid body, yet, as stated above, the invention is equally applicable to a projectile of the "shell" or explosive type.

50 When embodied in an explosive shell, the core member will function as an auxiliary projectile when the shell bursts upon impact with its target. The disintegration of the shell itself due to its explosion will free the core and the inertia of the latter will continue its movement into the target after the shell has exploded, thereby increasing considerably the effectiveness of the projectile.

55 I claim:

1. A projectile for firearms comprising a body portion provided with a through axial bore, and

a tubular core member mounted in said bore having a tapered forward end, said core member providing a passage through the projectile and being movable in said bore from a retracted position in which the tapered end is located within said bore to a forward operative position in which the tapered end projects beyond the body portion and forms the tip of the projectile nose, the rear end of said core being exposed to the pressure developed in the firearm when it is fired, said core being maintained by such pressure in its forward operative position during the traveling movement of the projectile through the barrel of the firearm.

2. A projectile for firearms comprising a body portion provided with a through axial bore, a tubular core member mounted in said bore having a tapered forward end, said core member providing a passage through the projectile and being movable in said bore from a retracted position in which the tapered end is located in the bore to a forward operative position in which the tapered end projects beyond the body portion and forms the tip of the projectile nose, and closure means operative while the projectile is in a firearm to close the passage through the core member, the rear end of said core member and said closure means being exposed to the pressure developed within the firearm when it is fired, whereby said core is maintained in its forward operative position by such pressure during the traveling movement of the projectile through the barrel of the firearm, said closure means thereafter becoming inoperative for this purpose after the projectile leaves the firearm.

3. A projectile for firearms comprising a projectile body having a through axial bore, a tubular core member mounted in said bore and having a tapered forward end, said core member providing a passage through the projectile and being movable in said bore from a retracted position in which the tapered end is located within the bore to an operative forward position in which said tapered end projects beyond the projectile body and forms the tip of the projectile nose, a sealing member for closing the end of the passage through the core member, and means for temporarily securing the sealing member to said core member, the rear end of the core member and the sealing member associated therewith being exposed to the pressure developed in the firearm when it is fired and being moved thereby from the retracted position to the forward operative position.

4. A projectile for firearms comprising a body portion provided with a through axial bore, a tubular core member mounted in said bore having a tapered forward end, said core member providing a passage through the projectile and being longer than the projectile body and also being movable in said bore from a retracted position in which the tapered forward end is located within said bore and the rear end projects beyond the base of the projectile to a forward operative position in which the tapered forward end of the core member projects beyond the projectile body and forms the tip of the nose thereof, and a sealing member temporarily secured to the rear end of the core member and closing the passage therethrough, the sealed rear end of the core member being exposed to the pressure developed within the firearm when it is fired, whereby such pressure moves the core member into its forward operative position.

5. A projectile for firearms comprising a body

portion provided with an axial bore, a tubular core member mounted in said bore having a tapered forward end, said core member providing a passage through the projectile and being movable in said bore from a retracted position in which the tapered end is located in the bore to a forward operative position in which the tapered end projects beyond the body portion and forms the tip of the projectile nose, said core member being longer than said body portion by an amount substantially equal to the distance between its retracted position and its forward operative position, whereby when in its forward operative position, the rear end thereof comes substantially flush with the base of the projectile, and a sealing member temporarily secured to the rear end of the core member and closing the passage therethrough, the sealed rear end of the core member being exposed to the pressure developed within the firearm when it is fired, whereby such pressure moves the core member from its retracted position to its forward operative position.

6. A projectile for firearms having a body portion provided with an axial bore, a tubular core member mounted in said bore having a tapered forward end, said core member forming a passage through the projectile and being movable in said bore from a retracted position in which the tapered end is located within said bore to a forward operative position in which the tapered end projects beyond the body portion and forms the tip of the projectile nose, and a sealing member at the rear end of the core member for temporarily closing said passage, whereby the pressure developed in the firearm when it is fired moves the core member to its forward operative position, said body member having means to prevent further forward movement of the core member after it reaches its operative position.

7. A projectile for firearms comprising a body portion provided with an axial bore, a tubular core member mounted in said bore having a tapered forward end, said core member providing a passage through the projectile and being movable in said bore from a retracted position in which the tapered end is located within said bore to a forward operative position in which the tapered end projects beyond the body portion and forms the tip of the projectile nose, and a sealing member at the rear end of the core member for temporarily closing said passage, whereby the pressure developed in the firearm when it is fired moves the core member to its forward operative position, said body portion having an interior rearwardly facing shoulder and the core having an annular forwardly facing shoulder which by its engagement with said rearwardly facing shoulder serves to prevent further forward movement of the core member after it has reached its operative position.

8. A projectile for firearms having a body portion provided with an axial bore, a core member mounted in said bore having a tapered forward end, said core member being movable in said bore from a retracted position in which the tapered end is located within the bore to a forward operative position in which the tapered end projects beyond the body portion and forms the tip of the projectile nose, said core member also having its rear end exposed to the pressure developed within the firearm when it is fired and adapted to be advanced by such pressure from its retracted position to its operative position, and means providing a cushioning action for the forward move-

ment of the core member and a stop to limit its forward movement.

9. A projectile for firearms having a body portion provided with an axial bore extending therethrough, a tubular core member mounted in said bore extending from one end to the other of the body portion and having a tapered forward end, said tubular core member providing a passage through the projectile from one end to the other and being movable in said bore from a retracted position in which the tapered end is located within said bore to a forward operative position in which the tapered end projects beyond the body

portion and forms the tip of the projectile nose, and a sealing member at the rear end of the core member for temporarily closing the passage therethrough, whereby the pressure developed in the firearm when it is fired moves the core member to its forward operative position, the peripheral portion of said sealing member extending beyond the periphery of the core member and operating to seal the joint between the core member and the wall of the bore while the projectile is traveling through the barrel of the firearm.

10 GEORGE NORMAN ALBREE.
